UNITED STATES PATENT OFFICE.

CHESTER J. VAN DOREN, OF OAK PARK, ILLINOIS, ASSIGNOR OF ONE-HALF TO H. T. DORRINGTON, OF CHICAGO, ILLINOIS.

APPARATUS FOR BOTTLING LIQUIDS.

Application filed September 18, 1920. Serial No. 411,172.

To all whom it may concern:

Be it known that I, CHESTER J. VAN DOREN, a citizen of the United States, and resident of Oak Park, county of Cook, and 5 State of Illinois, have invented certain new and useful Improvements in Apparatus for Bottling Liquids, of which the following is a specification and which are illustrated in the accompanying drawings, forming a part 10 thereof.

The invention relates to filling and corking bottles, and has as an object the provision of an apparatus for carrying out this 15 operation in multiple, with a minimum of individual attention to the bottles and with a minimum of hand work.

Illustrative embodiments of the apparatus provided by the invention are shown in the accompanying drawings, in which

20 Fig. 1 is a vertical longitudinal section of a cork press;

Fig. 2 is a perspective view of a bottle rack;

25 Figs. 3 and 4 are detail vertical sections showing a bottle rack, neck guide and cork rack, respectively, before and after the insertion of the cork;

Fig. 5 is a horizontal section on line 5—5 of Fig. 1;

30 Fig. 6 is a front elevation of the cork press;

Fig. 7 is a detail plan view of a cork rack partly broken away to show the neck guide and bottle rack;

35 Fig. 8 is a side elevation of a cork rack filling machine, partly broken away;

Fig. 9 is a detail horizontal section on line 9—9 of Fig. 8;

40 Fig. 10 is a detail side elevation of a displacing tool;

Fig. 11 is a central vertical section on line 11—11 of Fig. 8;

Fig. 12 is a horizontal section on line 12—45 12 of Fig. 8; and

Fig. 13 is a perspective view of a cam wheel.

The bottles to be filled are placed in a rack 10, shown in perspective in Fig. 2, which 50 rack has a plurality of compartments 11 which may each contain a plurality of bottles. The bottles are preferably filled by immersing the rack filled with bottles in liquid which may be placed in a vat 12 for the purpose. The bottles may be prevented from 55 floating by tilting the rack to a relatively

sharp angle while immersing the bottles. To allow the liquid to escape from the rack when the bottles and rack are lifted out of the vat, the bottom of the rack is made of foraminous material, as wire fabric 13.

60 The immersion of the bottles will fill them too full for corking. To displace a predetermined amount of liquid from each bottle a tool 14, shown in Fig. 10, is utilized. The fingers 15 of this tool are small enough to 65 freely enter the necks of the bottles, and are made of the right length to displace the desired amount of liquid when inserted their full length into the necks of the bottles. The spacing of the fingers 15 is adjusted to permit a finger to enter the neck of each bottle in a row when the bottles are contained in the rack 10. When the rack of filled bottles is removed from the vat it may be placed 70 with the wings 16, 17, resting on the sides 18 of the bed 19 of the cork press 20, which bed is shown as sloping toward the vat. If the tool 14 be applied while the rack is thus supported the displaced liquid, together with 75 that carried out of the vat on the bottle exteriors, will drain back into the vat.

80 To hold the bottle rack level and in the proper location while the corks are being pressed home, notches 21 may be formed in the sides 18 of the press bed, in which notches 85 the wings 16 may seat. As each row of corks is inserted the rack is moved forward one notch. The wings 17 rest upon the upper edges of the sides 18, and hence elevate that 90 side of the rack so as to hold the rack level.

To hold the necks of the bottles in accurate spacing and alignment a neck guide 22, in the form of a board with a hole 23 for each neck, is shown. The holes 22 are preferably 95 formed upwardly converging so as to guide the bottle necks to position when the rack is placed thereon. Cleats, as 24, may be provided to rest upon the partitions 25 of the bottle rack 10. Also dowel pins 26 and cleats 27 to locate and support the cork rack to be 100 described.

To hold the corks in alignment with the bottle necks a cork rack, as 28, is shown having holes 29 properly spaced to register with the holes 23 in the neck guide 22. Holes 30 105 are shown which are adapted to seat over the dowel pins 26 for the purpose of bringing the holes into register. The lower portions of the holes 29 are shown as of such a size 110 and taper that the size of tapered cork to be

used will fit therein and project downwardly therefrom nearly as far as the cleats 27 are thick.

The corks may be forced home by means of 5 plungers 31, carried by a reciprocating bar 32, which may be actuated by a foot lever 33 through the medium of a link 34, cross-bar 35, and vertical members 36 attached to the bar 32 and sliding in ways 37. A spring 38 10 is shown to hold the bar 32 in a normally elevated position. With the bottles in the rack filled and with their contents reduced by means of the tool 14, the wings 16 are placed in the first of the notches 21, the 15 neck guide is placed on the necks of the bottles, the cork rack filled with corks is placed on the dowel pins 26, and the foot lever 33 is forcibly depressed, whereby the first row of bottles in the rack will have the corks 20 forced into their necks. The depression of the bar 32 and fingers 31 will force the corks through the holes in the cork rack, compressing them to some extent in the process. The corks will not entirely recover from this 25 compression before they are finally seated in the bottles, and will therefore be more firmly held than if merely pressed in, in their normal condition.

The cork racks may be filled with corks by 30 means of the device shown in Figs. 8, 9, 11, 12 and 13. As shown this device comprises a cage 39, having a removable door 40 and preferably open at the bottom. The door 40 may have projecting flanges 41, 42, at bottom 35 and top coating with rabbets, whereby the door may be raised and then swung outward from the bottom. Springs, as 43, may be attached to the top of the door frame to hold the door down in its closed position. 40 For convenience in observing the operation of the device the sides of the cage and the door may be covered with wire fabric, as 44.

With the door removed the cork racks to be filled may be covered with a surplus of 45 corks poured loosely thereon, and may then be placed in the cage in ways 45. As shown the cage has a capacity of three racks.

As above explained the lower portions of 50 the holes in the cork racks are designed, in taper and size, to fit the corks. Immediately above this portion each hole has an offset, as at 46, Fig. 3, and above this offset each hole has the form of an inverted frustum of a 55 cone. The diameter of the lower portion of this inverted frustum being greater than that of the base of a cork to be handled, it is impossible for a cork to fall into any hole and be held therein frictionally except in its upright position, when it will fall to the 60 charged position shown at 47 (Figs. 3 and 8). Therefore, if a rack covered with corks be subjected to a series of violent upward jerks and the upward motion be suddenly arrested each time, all of the corks not frictionally held by the rack will be thrown 65

into the air and most of them will be caused to turn over to some extent and in some direction. It is found that a reasonable number of repetitions of such action will cause around 95% of the holes in the racks to be 70 become charged, when the surplus corks may be swept off and the few uncharged holes may be filled by hand.

The agitation of the racks may be readily produced if the parallel members 49, 50, be 75 allowed to project at each side of posts 51 and 52 as guides, and if the cage be suspended from some agitating means. As a suspension means there is shown an upright bar 53, bolted to members 49, which bar is 80 shown as secured to a spring in the form of bars 54, pivoted at 55 and rigidly secured to the frame beyond the pivot. The agitation referred to above may be produced by means of a cam wheel 56, having a series of cam 85 surfaces separated by shoulders 57, 58, 59, 60, of differing heights. The wheel 56 is shown as mounted on a shaft 61, turning in bearings 62, 63, and may be rotated by any desired device, as a crank 64. 90

The bar 53 projects upwardly between the frame members 65, and is pressed against the cam wheel 56 by the spring 54. When the wheel is rotated the cage will be alternately depressed and violently jerked upwardly, the upward motion being suddenly arrested, thus affecting the corks as above described. The difference in the successive jerks due to the difference in height of the cam shoulders will vary the effect on the corks so as to more efficiently agitate them for the purpose intended, since a succession of identical movements might conceivably turn any individual cork completely over one or more turns at each movement, thus failing to change its position while at rest, while a jerk of given intensity followed by 100 one of greater or less intensity could not have this result. If, for example, the jerking movement produced by the shoulder 57 105 were just sufficient to completely overturn a particular cork, the movement caused by the shoulder 58, which is either greater or less than that caused by the shoulder 57, would either have the effect of more than completely overturning the cork, or would fail to 110 completely overturn the same. 115

When the racks have been charged they may be removed from the cage, the surplus corks being swept from the surface as they are withdrawn. A tray 66 may be placed in the base of the device to receive the corks as 120 swept off.

Minor changes may be made in the form of the devices and in the process without departing from the spirit of the invention. 125

I claim as my invention—

1. A cork rack charging device comprising, in combination, a cork rack having a plurality of holes adapted at their lower 130

- portions each to fit a tapered cork projecting below the board, each hole having an abrupt increase of diameter forming an offset adjacent the position occupied by the base of 5 a cork seated in said hole, said increased diameter being greater than the greatest diameter of the tapered cork, said hole being of upwardly increasing diameter above said offset, and means to subject said rack to suddenly arrested upward movements. 10
2. A cork rack charging device comprising, in combination, a cork rack having a plurality of holes each adapted at its lower end to fit a tapered cork and having an offset adjacent the position occupied by the large end of the cork when seated in the hole, and being of upwardly increasing diameter above said offset, means to subject said rack to suddenly arrested upward movements. 15
3. A bottle corking device comprising a press having a sloping bed, inclined side members on said bed having notches, a bottle rack adapted to contain a plurality of rows of bottles, wings at each end of the sides of the rack, one set of wings being adapted to seat in said notches, the depth of the notches being such as to level the rack when the other set of wings rests on the edges of the sides, and means on said press to drive home a plurality of corks simultaneously. 20
4. A bottle corking device comprising, in combination, a bottle rack having openings adapted to fit the necks of the bottles to be corked, dowel pins projecting upwardly from said rack, a removable cork rack having openings to receive said dowel pins, cork openings corresponding to the openings in the bottle rack, and means for driving a plurality of corks simultaneously through the cork racks into the bottles. 25
5. A bottle corking device comprising, in combination, a removable bottle rack having openings adapted to fit the necks of the bottles to be corked, dowel pins projecting upwardly from said rack, a removable cork rack having openings to receive said dowel pins, cork openings corresponding to the openings in the bottle rack spacing means between the racks, and mean for driving a plurality of corks simultaneously through the cork racks into the bottles. 30
6. A cork rack charging device comprising, in combination, a cork rack having a plurality of holes each adapted to its lower end to fit a tapered cork and having an offset adjacent the position occupied by the large end of the cork when seated in the hole, and each hole being of upwardly increasing diameter above said offset, and means for subjecting said rack to a series of suddenly arrested movements of unequal intensity. 35
